CIRCUIT BREAKER MECHANISM

James M. Cumming, Turtle Creek, Pa., assignor
to Westinghouse Electric & Manufacturing
Company, East Pittsburgh, Pa., a corporation
of Pennsylvania

Application May 30, 1942, Serial No. 445,153

18 Claims. (Cl. 200—81.5)

The invention relates to circuit breakers, which may be of the automatic reclosing type, having power actuated operating mechanism operable to effect normal closing and/or quick automatic reclosing operation of the breaker, the mechanism including means for manually closing the breaker.

In order to obtain a quick reclosing of circuit breakers where the maximum allowable time limit is of the order of 20 cycles or less from the initiation of the fault, it is necessary to initiate the reclosing operation before the breaker reaches full open position, and it is important that the mechanism should have as few moving parts as possible. Another requirement is that the breaker must be capable of being tripped open at high speed even though closing power is being delivered to the mechanism, i. e., the breaker must be power trip-free. Quick reclosing operating mechanisms have been made which are power trip-free and require only a single mechanism lever, but they have been handicapped by their inability to be mechanically trip-free of the manual closing means without the use of additional levers or an additional trip device. All mechanisms for operating circuit breakers must have provision for hand closing and when hand closed against a faulted line must be mechanically trip-free in order to protect the operator.

An object of the invention is the provision of a circuit breaker with an improved operating mechanism which satisfactorily fulfills all of the requirements mentioned above yet which is simple and inexpensive to manufacture and has very few moving parts.

Another object of the invention is the provision of a circuit breaker with an improved and simple operating mechanism that is power trip-free on power operation and mechanically trip-free during hand closing operations.

Another object of the invention is the provision of a circuit breaker with an improved operating mechanism having power actuated operating mechanism operable to effect normal closing or quick automatic reclosing of the breaker and having a normally stationary manual closing means, the breaker being power trip-free on power operation and mechanically trip-free of the manual closing means.

Another object of the invention is the provision of a circuit breaker with an improved operating mechanism utilizing only a single moving operating lever on power closing or reclosing operations, the operating lever being operatively related in a non-mechanically trip-free manner to the breaker and the power closing means and

having a mechanically trip-free connection with the manual closing lever.

Another object of the invention is the provision of a circuit breaker with an operating mechanism having a non-trip-free operative connection between the breaker and the power closing means and a trip-free connection between the breaker and the manual closing lever, and a single latching means and trip device for releasing the breaker to cause opening thereof and tripping the breaker free of the manual closing lever.

Another object of the invention is the provision of a circuit breaker with an operating mechanism comprising a fluid motor operatively related in a non-mechanically trip-free manner to the breaker for closing and quickly reclosing the breaker, a manual closing lever having a trip-free connection to the breaker, and a single trip device for releasing the breaker to cause opening thereof notwithstanding the supply of fluid pressure to the motor and irrespective of the position of the closing lever.

Another object of the invention is the provision of a circuit breaker with an operating mechanism as described in the preceding paragraphs, wherein the single trip device operates to trip the breaker free of the manual closing lever, and a dump valve associated with the fluid motor is operated simultaneously with the trip device to permit high speed opening of the breaker unopposed by fluid pressure.

Another object of the invention is the provision of a circuit breaker with an improved operating mechanism comprising a compressed gas actuated closing motor operable to quickly reclose the breaker, and a manual closing lever which remains stationary during power and automatic operation of the breaker, the breaker being power trip-free on power operation and mechanically trip-free of the manual closing lever.

The novel features that are considered characteristic of the invention are set forth in particular in the appended claims. The invention itself, however, both as to structure and operation together with additional objects and advantages thereof, will be best understood from the following detailed description of one preferred embodiment of the invention when read in conjunction with the accompanying drawings, in which:

Figure 1 is a view, partly in section, of a circuit breaker and operating mechanism embodying the features of the invention, the parts being shown by full lines in the closed circuit position, and the circuit breaker being shown schematically;

Fig. 2 is a plan view, partly in section, of the operating mechanism shown in Fig. 1;

Fig. 3 is a sectional view of the operating mechanism taken substantially at right angles to the section of Fig. 1;

Fig. 4 is a fragmentary view, partly in section, of the operating mechanism showing the manual operating lever in the raised position ready to close the breaker; and

Fig. 5 is a schematic diagram illustrating the control circuit for controlling the operation of the circuit breaker.

Referring to the drawings, the circuit breaker shown schematically at 7 in Figure 1 may be of any conventional construction either of the oil break or air break type. As schematically shown, the circuit breaker includes stationary contact means 9 and cooperating movable contact means 11 for controlling a main circuit represented diagrammatically by the line 13. Although illustrated as a single pole circuit breaker, it will be understood that the circuit breaker may be a multipole circuit breaker having a set of contact means 9-11 for each pole or unit thereof with the movable contact means mechanically connected for simultaneous operation in the usual manner. The circuit breaker is biased to open circuit position by means of an accelerating spring shown schematically at 15, and the breaker is mechanically connected to the operating mechanism indicated generally at 17 by a suitable connecting means. The connecting means is represented schematically as comprising a direction changing lever 19 pivoted at 21, one end of the lever being connected to the breaker lift rod 23 of insulating material. The other end of the lever 19 is pivotally connected to the breaker operating rod 25 which is in turn mechanically connected to the operating mechanism 17.

The operating mechanism 17 comprises a main casting 27 which is formed to provide an operating cylinder 29 closed at the upper end by an integral part of the casting. A closure member 31 is secured to the lower end of the cylinder 29 to close this end of the cylinder, and this closure member has a relatively large port 33 therein which is open to atmosphere. An operating piston 35 is reciprocally movable in the cylinder 29 and has a tubular rod portion 37 formed integral therewith which slidably extends in a fluid tight manner through an opening provided therefore in the upper end of the cylinder. The operating piston 35 is operatively related at all times to the circuit breaker operating rod 25, and is adapted to be operated by compressed air to effect normal closing or quick automatic reclosing operation of the circuit breaker.

A manually operable closing lever 39 is pivotally mounted at its left-hand end on the upper portion of the casting 27. The manual closing lever is made up of a pair of spaced levers 41 (Fig. 2) rigidly joined at their right-hand ends to an operating handle 43. The other ends of the levers 41 are pivotally mounted by short pivot pins 45 (Fig. 2) on a pair of spaced bifurcated projections 47 formed integral with the casting 27 and projecting upwardly therefrom.

An operating or latching lever 49 is pivotally mounted at one end on a pivot shaft 51 carried by the manual closing lever 39 adjacent the handle 43. The lever 49 is disposed within the space between the levers 41 that make up the manual closing lever 39, and this lever 49 has spaced apart parallel sides (Fig. 2) which are rigidly joined together by cross members 53.

The manual closing lever is held locked down in the closed position shown in Fig. 1 at all times, except when the breaker is being manually closed, by means of a manually operable latch 55 that is pivoted on a pivot pin 57 supported by a portion of the casting 27. The latch 55 engages a roller 59 carried on the pivot pin 51, and the latch is biased to latching position by a compression spring 61. A handle 62 is provided on the latch 55 for moving the latch to released position to release the manual closing lever when it is desired to close the circuit breaker by hand.

10 The circuit breaker operating rod 25 is pivotally connected by a pivot pin 63 to the operating lever 49 intermediate the ends of the lever, the pivot pin 63 extending transversely through the sides of the lever 49 and engaging openings in a bifurcated connecting element 65 on the lower end of the rod 25 which is disposed between the sides of the lever 49. A short connecting link 67 connects the operating lever 49 to tubular piston rod 37, the upper end of the link being pivotally connected to the pivot pin 63 and the lower end being pivotally connected to the piston rod 37 by a pivot pin 69. The circuit breaker is thus operatively connected in a non-trip-free manner to the operating piston 35.

15 A short shaft 71 is carried by the free end of the operating lever 49 between the sides thereof, and a latch roller 73 is rotatably mounted on the short shaft. In the closed circuit position of the breaker and mechanism, the free end of the operating lever 49 lies between the spaced pivot supports 47, and the axis of the short shaft 71 and latch roller 49 is held in alignment with the fixed pivot axis 45 of the manual closing lever 39, as shown in Fig. 1.

The breaker operating lever 49 is adapted to be held in the closed position shown by the full lines in Fig. 1 to hold the circuit breaker closed, by means of a high speed latching mechanism comprising a main latch 75 which is pivoted on the casting 27 by means of a pivot pin 77. The main latch 75 is biased to latching position by a spring 79, and the latch is adapted to engage and restrain the latch roller 73 carried by the free end of the breaker operating lever 49. The configuration of the face of the main latch 75 is such that this latch alone will not hold the breaker operating lever 49 in closed position against the opening bias of the breaker unless the main latch is itself held in latching position.

An auxiliary latch 81 is provided for normally engaging and holding the main latch 75 in latching position. The auxiliary latch 81 is pivoted by a pivot pin 83 on the casting 27 and has a latch projection 85 which is adapted to engage under a cooperating latch projection of the main latch 75. The auxiliary latch 81 is biased to latching position by a compression spring 87 seated in a recess in the casting 27; and the latch is provided with a projection 89 which extends directly over the upper end of the trip plunger 91 of an electromagnetic trip device 93. The trip device 93 comprises in addition to the trip plunger 91, an E-shaped core 95 of magnetic material, an energizing winding 97 wound on the center leg of the core, and a movable armature 99 cooperating with the core. The trip plunger 91 is secured to the center of the armature 99 and slidably extends upwardly through a guide opening in the center portion of the core and through an opening in the horizontal portion of the casting 27.

75 When the trip device 93 is energized, the trip

plunger 91 is moved upwardly by the armature 99 and rotates the auxiliary latch 81 clockwise to disengage the main latch 75, whereupon the acceleration spring 15 of the circuit breaker moves the circuit breaker to open circuit position. The opening movement of the circuit breaker rotates the operating lever 49 in a clockwise direction to the position indicated by the dotted lines in Fig. 1, this position corresponding to the open position of the circuit breaker. During the initial opening movement of the operating lever 49, the latch roller 73 forces the main latch 75 in a clockwise direction as it clears the latch. In order to prevent the auxiliary latch 81 from being returned to latching position until the breaker operating lever 49 is returned to closed position, there is provided a U-shaped holding lever 101, the legs of which are pivotally mounted on the pivot pin 83 on opposite sides of the auxiliary latch 81. The holding lever is biased in a clockwise direction by a spring 103 which is stronger than the latch spring 87. A projection 105 on the free end of the holding lever is disposed directly beneath the free end of the operating lever 49 so that the holding lever is held down in inoperative position when the operating lever 49 is in closed position. However, when the operating lever is released, the holding lever is rotated in a clockwise direction and a projection 107 thereof engages and holds the auxiliary latch 81 in unlatched position until the breaker operating lever 49 is returned to closed position.

The operating piston 35 is adapted to be moved downwardly in the cylinder 29, to close or automatically reclose the circuit breaker, by compressed air from an auxiliary air reservoir or tank 111 (Fig. 5), the compressed air being admitted to the upper end of the operating cylinder through an inlet passage 113 (Fig. 3) controlled by an inlet valve 115. Compressed air is supplied to the auxiliary tank 111 from a main tank (not shown), in which air is stored and maintained at a predetermined pressure by a suitable compressor unit, not shown.

The inlet valve 115 is carried on a valve stem 117, and this valve is biased closed by a compression spring 119 disposed in the valve housing and encircling the lower portion of the valve stem. A second valve element 121 carried by the valve stem 117 cooperates with an atmosphere exhaust passage and serves to permit air to be exhausted from the operating cylinder 29 when the inlet valve 115 is closed. The inlet valve 115 is adapted to be operated to open position by means of an electromagnet 123 comprising a U-shaped stationary core 125, an energizing winding 127 and a T-shaped armature 128. The lower end of the armature engages the top of the valve stem 117, and when the electromagnet is energized the armature is moved downwardly to attracted position to open the inlet valve 115 and close the exhaust valve 121. Compressed air is thereupon admitted to the upper end of the operating cylinder 29 and drives the piston 35 downwardly to effect closing of the circuit breaker.

The mechanism is provided with means for automatically controlling the rate of flow of compressed air to the operating cylinder. This means is fully disclosed in the copending application of H. L. Peek and J. M. Cumming, Serial No. 445,881, filed June 5, 1942, and assigned to the assignee of the present invention.

This means, by itself, forms no part of the present invention, and hence will only be very briefly

described herein as comprising a valve 129 (Fig. 3) which is interposed in the inlet passage 113. The valve is biased by a spring 130 to an open position shown in which a groove 131 on the valve 129 permits air to flow through the passage 113 at a high rate into the operating cylinder 29. The valve remains in open position during the major portion of the opening stroke of the piston and near the end of the opening stroke it is moved to a closed position by the piston and is retained in closed position by a spring pressed ball, not shown. A small air passage (not shown) in the casting 27 bypasses the valve 129 to permit compressed air to flow into the operating cylinder at a throttled rate during the first part of the breaker closing operation started from the full open position of the breaker. As the breaker approaches closed position, a projection 132 carried by the breaker operating lever 49 engages and moves the valve 129 to the open position, the opening movement being completed by the valve biasing spring 130. When the valve 129 is actuated to open position, compressed air is admitted to the cylinder at a faster rate to provide additional driving power to overcome the relatively heavy contact load of the breaker which is picked up during the final portion of the closing operation. The construction of the valve is such that it remains open during quick reclosing operations to provide the additional larger quantity of compressed air necessary to quickly reverse the movement of the circuit breaker and quickly reclose the breaker.

It was previously pointed out that the circuit breaker is operatively connected to the operating piston 35 at all times, and hence is not mechanically trip-free of the piston. In order to make the circuit breaker power trip-free, that is, capable of being tripped open at high speed on power closing or reclosing against a faulted line even though compressed air is being delivered to the operating cylinder, the operating cylinder is provided with an air pressure exhaust means for causing quick collapse of air pressure in the cylinder 29 whenever the trip device 93 is operated. This air pressure exhaust means comprises a large exhaust port 133 formed in the side wall of the operating cylinder and communicating with an atmosphere exhaust passage 135 controlled by an exhaust or dump valve 137. The exhaust port 133 and exhaust passage 135 are of larger size than the inlet passage 113, so that when the dump valve is opened, it will cause quick collapse of air pressure in the cylinder 29, thereby permitting quick reversal of movement of the operating piston and high speed opening of the circuit breaker unretarded by air pressure above the operating piston. The dump valve 137 is in the form of a cup-shaped piston type valve and is biased to closed position by a helical compression spring 139 disposed in the valve housing and engaging the underside of the dump valve. The valve element 137 is slidably movable in a cylinder formed in the valve housing, and opening of the dump valve is initiated by means of an electromagnet 141. The electromagnet comprises a U-shaped stationary core 143, an energizing winding 145 and an armature 147. A stem 149 connected to the armature extends loosely through an opening in the top of the dump valve 137 and has an enlarged head thereon which engages the top of the valve. The valve 137 is slidable on the stem 149 and is adapted to be partly opened upon energization of the electromagnet 141. When the valve has been partly opened by the operation of the electromagnet 141, any compressed air

present in the operating cylinder 29 flows out to atmosphere over the top of the valve 137 and the air pressure forces the dump valve quickly to the full open position compressing the relatively light biasing spring 139. The electromagnet 145 is adapted to be energized simultaneously with the trip device 93 and for this purpose the winding 145 of the electromagnet 141 is connected in parallel with the winding of the trip device 93, as shown in Fig. 5.

Referring now to Fig. 5 which diagrammatically shows the circuits for electrically controlling the circuit breaker, 151 and 153 designate a pair of supply conductors connected to a source of electric energy (not shown). The winding 127 of the electromagnet 123 which controls the admission of compressed air to the operating cylinder for automatically reclosing the circuit breaker is connected in an energizing circuit 155 extending from the supply conductor 151 through the winding 127, through back contacts 157 of a release relay R and front contacts 159 of an operating relay O to the supply conductor 153. The energizing winding of the operating relay O is connected in an energizing circuit which extends from the supply conductor 153, through a conductor 161, back contacts 163 of the release relay R, energizing winding of the operating relay O, conductor 165 and through a manual control switch 167 for controlling the normal power closing operation of the circuit breaker, to the opposite supply conductor 151. The energizing winding of the release relay R is connected in an energizing circuit which extends from the supply conductor 153, through conductor 169, through an auxiliary switch 171 that is closed when the circuit breaker reaches closed position, through the energizing winding of the release relay R, through front contacts 173 of the operating relay O and conductor 175 to the supply conductor 151. A locking circuit is also provided for maintaining the release relay R energized after closing of the auxiliary switch 171 until the manual closing control switch 167 has been opened. The latter locking circuit extends from the conductor 153, through conductor 161, front contacts 179 of release relay R, through the energizing winding of the release relay, conductors 177 and 165 and through the manual closing control switch 167 to the supply conductor 151.

The winding 97 of the trip device 93 and the winding 145 of the dump valve electromagnet 141 are connected in parallel in an energizing circuit which extends from the supply conductor 153, through conductor 169, through an auxiliary switch 181 that is closed when the circuit breaker is closed, through the windings 97 and 145 in parallel, through contacts 183 of a fault responsive overload protective relay 185, and through conductor 187 to supply conductor 151. The fault responsive relay is arranged to be operated to close its contacts 183 upon the occurrence of a predetermined overload or short circuit in the main circuit 13 controlled by the breaker. For this purpose, the energizing winding of the protective relay 185 is arranged to be energized by a current transformer 189 associated with the main circuit conductor 13.

The circuit breaker may also be tripped open by means of a manually operable trip control switch 191 which is connected in shunt to the contacts 183 of the protective relay.

The circuit breaker 7 is adapted to be automatically reclosed immediately following interruption of the circuit by the circuit breaker,

through the agency of a reclosing relay 193. Automatic reclosing movement of the circuit breaker is preferably initiated immediately after the circuit breaker has interrupted the circuit and before the circuit breaker reaches the full open position. Reclosing relay 193 has its contacts 195 connected in shunt relation to the contacts of the manual control closing switch 167. A manually operable switch 197 is provided in

series with the contacts 195 for the purpose of preventing quick automatic reclosing operation of the circuit breaker if automatic reclosing is not desired. The energizing winding of the reclosing relay 193 is connected in an energizing circuit 199 which extends from the supply conductor 153, through the winding of the reclosing relay 193, through contacts 201 of the protective relay 185 and through an adjustable auxiliary switch 203 which is adjusted to close during the initial opening movement of the circuit breaker, and through conductor 187 to the supply conductor 151.

The operation of the mechanism is as follows: Assuming the circuit breaker to be in closed position, as shown in Fig. 1, when a predetermined overload or short circuit occurs in the main circuit 13 controlled by the breaker, the protective relay 185 is immediately energized and closes its contacts 183 to effect energization of the trip device 93. When the trip device is energized, it moves the trip plunger 91 upwardly to cause the auxiliary latch 81 to release the main latch 75, thereby releasing the breaker operating lever 49. The circuit breaker is immediately moved in opening direction by its biasing spring 15. The main circuit is interrupted during the first part of the opening movement of the breaker by the time the circuit breaker has opened only a part of its full open distance.

Assuming the manual switch 197 to be closed, quick automatic reclosing operation of the circuit breaker will be caused to take place as soon as the circuit breaker is opened through a predetermined distance less than full open distance. Quick automatic reclosing operation is initiated by the reclosing relay 193 in response to closing of its energizing circuit by the contacts of the auxiliary switch 203. The contacts 201 of the protective relay are closed simultaneously with the contacts 183 upon operation of the protective relay, thus preparing the energizing circuit for the reclosing relay 193. When the relay 193 is energized, it closes its contacts 195, thereby effecting energization of the operating relay O. The operating relay O, in turn, completes an energizing circuit for the inlet valve controlling electromagnet 123, thereby causing opening of the main inlet valve 115. Compressed air is thereupon admitted to the upper end of the operating cylinder 29 quickly moving the piston 35 downwardly to reclose the circuit breaker. These operations occur substantially instantaneously so that reclosing movement of the operating piston 35 is initiated very shortly after the circuit has been interrupted and before the breaker reaches the full open position. The operating relay O remains energized until the circuit breaker reaches the closed position at which time the release relay R becomes energized due to closing of the contacts of the auxiliary switch 171. The release relay thereupon opens the energizing circuit of the operating relay at the contacts 163 and becomes itself deenergized upon opening of the contacts 173 of the operating relay. If the condition which caused the overload or

short circuit has been removed by the time the circuit breaker completes the circuit upon quick automatic reclosing operation, the circuit breaker remains closed and the control circuits assume their normal condition shown in Fig. 5. However, if the fault condition which causes the overload or short circuit is still present by the time the circuit breaker reaches closed position, the protective relay 185 is again energized the instant the main circuit is completed again causing energization of the trip device 81, and at the same time causing the energization of the dump valve electromagnet 141 which is in parallel circuit with the trip device. Consequently, the latching means 75 will again be released and at the same time the electromagnet 141 will initiate opening of the dump valve 137, thereby causing air pressure to be quickly exhausted to atmosphere even though the inlet valve 115 may still be open at this time. Thus the circuit breaker is caused to quickly reverse its movement and start opening even though the inlet valve may be open at this time. The opening movement of the circuit breaker is substantially unretarded due to the quick collapse of air pressure in the operating cylinder 29. A lockout device 205 of any conventional construction may be provided in the circuit of the reclosing relay 193 to prevent more than one quick automatic reclosing operation of the circuit breaker. The circuit breaker proceeds to the full open position and remains open after one unsuccessful attempt at quick reclosure.

Normal closing operation of the circuit breaker from the full open position is accomplished by closing the manual control switch 161. Closing of this switch completes an energizing circuit for the operating relay O which, in turn, completes the energizing circuit for the inlet valve controlling electromagnet 123, thereby causing compressed air to be admitted to the operating cylinder to close the circuit breaker. The operating relay O remains energized until the circuit breaker reaches closed position, whereupon the release relay R becomes energized due to closing of the contacts of the auxiliary switch 171. The release relay when thus energized opens the energizing circuit of the operating relay O at the contacts 163, thereby causing deenergization of the operating relay and the inlet valve electromagnet 123. Opening of the front contacts 173 of the operating relay deenergizes the release relay R and the system is restored to normal. If the circuit breaker should be closed against an overload or short circuit, the protective relay 185 will be operated to trip the breaker in the previously described manner, also causing opening of the dump valve 137.

The circuit breaker may be manually tripped open by closing the manual trip control switch 191 which effects energization of the trip device 93, thereby tripping the circuit breaker. The circuit breaker may also be manually tripped at the breaker station by means of a manual trip control lever 207 (Fig. 1) which when operated moves the trip plunger 91 upwardly to release the circuit breaker latching means.

As previously pointed out, the manually operable closing lever 39 remains locked down in the closed position, as shown in Fig. 1, by the manually operable latch 55 at all times except during manual closing of the circuit breaker. The pivot 51 of the breaker operating lever 49 is thus always held in a fixed position by the latch 55, except when the breaker is being manually closed. Consequently, the mechanism utilizes only a

single operating lever during automatic or electrical operation of the circuit breaker.

Assuming the circuit breaker to be in the open position with the breaker operating lever in the open position indicated by the dot-dash line in Fig. 1, if it is desired to manually close the circuit breaker, the operator moves the manually operable latch 55 to released position by the operating handle 62, thereby releasing the manual closing lever 39. The operator then moves the manual closing lever 39 upwardly in a counter-clockwise direction about its fixed pivot axis 45 to the position shown in Fig. 4. This upward movement of the manual closing lever causes the breaker operating lever 49 to be rotated in a counterclockwise direction about the pivot pin 63 as a center, thereby causing the free end of the breaker lever 49 to be moved down to latching position where it is reengaged by the main latch 75 and held in latched position by the latching mechanism. The manual closing lever 39 is then moved downwardly to the position shown in Fig. 1 until it becomes relatched by the latch 55. This downward movement of the closing lever from the position shown in Fig. 4 to that shown in Fig. 1 moves the circuit breaker to closed position. It will be noted that the circuit breaker is mechanically trip free of the manual closing lever 39, since if the circuit breaker should be manually closed against an overload or short circuit, the trip device 93 will be operated as soon as the circuit is completed, thereby effecting release of the main latch 75 and permitting the circuit breaker to be quickly moved to open position by its spring 15 irrespective of the position of the manual closing lever 39 even though the operator holds the closing lever 39 in closed position.

The invention provides a simple and inexpensive circuit breaker operating mechanism embodying a power actuated closing means or fluid motor operable to effect quick automatic reclosing of the circuit breaker. The mechanism utilizes a minimum number of moving parts during automatic and power operation and the breaker is operatively related at all times to the closing means thereby permitting high speed fractional stroke automatic reclosing. The breaker, however, is power trip-free, i. e., it is capable of opening notwithstanding the supply of closing compressed air to the closing motor. The mechanism is provided with a manual closing lever which is mechanically trip-free of the breaker and remains stationary at all times except when the breaker is being manually closed. A single trip device releases the breaker to permit opening thereof and trips the breaker free of the manual closing lever.

While the invention has been disclosed in accordance with the provisions of the patent statutes, it is to be understood that various changes in the structural details and arrangement of parts thereof may be made without departing from the essential features of the invention. It is desired, therefore, that the language of the appended claims be given the broadest reasonable interpretation permissible in the light of the prior art.

I claim as my invention:

1. In combination, a circuit breaker biased to open circuit position, power operated closing means for closing the circuit breaker, latching means for holding said breaker in closed position, a trip device operable to effect release of said latching means and thereby cause opening of said breaker, said circuit breaker remaining

operatively related to and under the immediate control of said power operated closing means at all times, and manually operable means for closing said breaker, said latching means when released causing opening of said breaker irrespective of the position of said manually operable closing means.

2. In combination, a circuit breaker biased to open circuit position, power operated closing means operatively connected to the breaker for closing said breaker, holding means for releasably holding said breaker in closed circuit position, a trip device operable to release said holding means to cause opening of the breaker, said circuit breaker remaining operatively connected to said power operated closing means when released by said holding means, a manually operable lever for closing said breaker, said holding means when released tripping said breaker free of said manually operable lever.

3. In combination, a circuit breaker biased to open circuit position, power operated closing means operatively related to said circuit breaker for closing the breaker, latching means for releasably holding said circuit breaker in closed circuit position, a trip device operable to effect release of said latching means to thereby cause opening of the breaker, means operated simultaneously with said trip device for effecting deenergization of said power operated closing means, and a manually operable closing lever for closing said breaker, said latching means when released permitting opening of said circuit breaker irrespective of the position of said manually operable closing lever.

4. In combination, a circuit breaker, power operated mechanism operable to close the breaker, a manually operable closing lever for manually closing the breaker, said lever having a fixed pivot, releasable locking means for holding said closing lever in closed position, a breaker lever pivoted to said closing lever adjacent the free end of the closing lever, said breaker lever being non-releasably connected to said breaker and operatively related in a non-trip-free manner to said power operated mechanism, automatic latching means engageable with said breaker lever for releasably holding said circuit breaker in closed circuit position, and a trip device operable to effect release of said latching means and thereby cause opening of said breaker.

5. In combination, a circuit breaker, a power operated device operable to close the breaker, a manually operable closing lever for manually closing the breaker, said lever being mounted on a fixed pivot, releasable locking means for holding said lever in a closed position, a breaker lever pivoted to said closing lever, said breaker lever being non-releasably connected to said breaker and operatively related in a non-trip-free manner to said power operated device, automatic latching means engageable with said breaker lever for releasably holding said circuit breaker in closed circuit position, a trip device operable to effect release of said latching means and breaker lever to trip the breaker, and means operated simultaneously with said trip device for deenergizing said power operated device.

6. Operating mechanism for a circuit breaker comprising a breaker lever having a non-trip-free connection to the breaker, a power operated device operatively related in a non-mechanically-trip-free manner to said lever and operable to effect closing operation of the breaker, latching means engageable with said breaker lever for

releasably holding said breaker in closed circuit position, a trip device operable to release said latching means to thereby trip the breaker, means operated simultaneously with said trip device for effecting deenergization of said power operated device, a manually operable closing lever for closing the breaker, said latching means when released permitting opening of said breaker and breaker lever irrespective of the position of said closing lever.

5 7. Operating mechanism for a circuit breaker comprising power operated closing means for closing the breaker having a non-trip-free operative relation to the breaker, latching means for releasably holding the breaker in closed position, a trip device operable to effect release of said latching means to thereby trip the breaker, means operated simultaneously with said trip device for effecting deenergization of said power operated closing means, a manually operable closing lever for closing the breaker, and trip-free means operatively relating said closing lever to the breaker, said latching means when released tripping the breaker free of said closing lever.

20 8. Operating mechanism for a circuit breaker comprising a power operated device for closing the breaker, a non-mechanically-trip-free connecting means between the breaker and said power operated device, latching means for releasably holding the breaker in closed position, a trip device operable to effect release of said latching means to thereby trip the breaker, means operated simultaneously with said trip device upon operation thereof for effecting deenergization of said power operated device, a manually operable closing lever for closing the breaker, and a mechanically-trip-free connection between the breaker and said closing lever, said latching means when released mechanically tripping the breaker free of the manually operable closing lever.

25 9. Operating mechanism for a circuit breaker comprising power operated closing means operatively related to the breaker for closing the breaker, tripping means having only a single trip coil operable to trip the breaker, said breaker remaining operatively related to and under the immediate control of the power operated closing means at all times, and manually operable means for closing the breaker, said trip coil when operated tripping the breaker free of said manually operable means.

45 10. In combination, a circuit breaker, power operated closing means for closing the circuit breaker, tripping means comprising a single trip coil operable to cause opening of the circuit breaker, said circuit breaker remaining operatively related to and under the immediate control of said power operated closing means during the opening operation of the breaker, and manually operable means for closing said circuit breaker, said tripping means being operable to trip said breaker free of said manually operable closing means.

60 65 11. In combination, a circuit breaker, power operated closing means for closing said circuit breaker, means for energizing said power operated closing means, a single tripping device operable to cause opening of said circuit breaker, said circuit breaker remaining operatively related to and under the control of said power operated closing means at all times, means operated simultaneously with said tripping device for deenergizing said power operated closing means, and a manually operable closing member

70 75

for closing said circuit breaker, said tripping device when operated causing opening of said breaker irrespective of the position of said manually operable closing member.

12. In combination, a circuit breaker, a fluid motor arranged to be connected to a source of fluid pressure for closing the breaker, means operatively relating the motor to the breaker, a venting valve for exhausting fluid from said motor, tripping means having a single trip coil operable to trip the breaker, means operated simultaneously with said tripping means for opening said venting valve to allow high speed opening of the breaker, said breaker remaining operatively related to said fluid motor and under the control thereof at all times, and a manually operable closing lever for closing said breaker, said trip coil when operated tripping said breaker free of said closing lever.

13. In combination, a circuit breaker, a fluid motor arranged to be connected to a source of fluid pressure for closing the breaker, means operatively relating the motor to the breaker, latching means for releasably holding the breaker in closed position, a trip device operable to release said latching means to thereby trip the breaker, means operated simultaneously with said trip device for exhausting fluid from said motor to permit high speed opening of the breaker, and manually operable means for closing the breaker, said latching means when released tripping said breaker free of said manually operable means.

14. In combination, a circuit breaker biased to open position, a fluid motor for closing the breaker, a non-trip-free connection between said motor and the breaker, means for supplying fluid pressure to said motor, latching means for releasably holding said breaker in closed position, a dump valve for exhausting fluid from said motor to permit high speed opening of the breaker notwithstanding the supply of fluid pressure to said motor, a trip device operable to release said latching means, said dump valve being opened simultaneously with the operation of said trip device, and a manually operable closing lever for manually closing the breaker, said latching means when released causing opening of the breaker irrespective of the position of said manually operable closing lever.

15. A compressed gas operating mechanism for a circuit breaker comprising a cylinder, a piston in said cylinder operable to close the breaker, a non-trip-free operative connection between said piston and the breaker, means for supplying compressed gas to said cylinder to close the breaker, latching means for releasably holding the breaker in closed position, a dump valve for exhausting gas from said cylinder on the working side of the piston to permit high speed opening of the breaker notwithstanding the supply of compressed gas to said cylinder, a trip device operable to release said latching means to trip the breaker, means for simultaneously causing opening of said dump valve, a manually operable closing lever for closing the breaker having a mechanically trip-

free connection to the breaker, said latching means when released effecting release of said trip-free connection to trip the breaker free of said closing lever.

16. An operating mechanism for a circuit breaker comprising a manually operable closing lever pivoted to a fixed support, a manually operable latch for normally holding said lever in closed position, a cylinder and a piston therein operable to close the breaker, a breaker lever pivotally connected to said closing lever and having a non-trip free operative connection to said breaker and to said piston, latching means engageable with said breaker lever for releasably holding the breaker closed, means for supplying compressed air to said cylinder to effect closing operation of the breaker, a dump valve for dumping air from said cylinder to atmosphere to permit high speed opening of the breaker, a trip device operable to release said latching means to thereby trip the breaker, and means operated simultaneously with said trip device for causing opening of said dump valve.

17. In combination, a circuit breaker, a fluid motor including a cylinder and a piston operatively related to the breaker for closing the breaker, a source of fluid pressure and a control valve for supplying fluid pressure to said cylinder to close the breaker, said breaker remaining operatively related to said piston and under the control thereof at all times, a latch for holding said breaker in closed position, a dump valve for exhausting fluid from said cylinder on the working side of the piston to permit high speed opening of the breaker notwithstanding the flow of fluid under pressure from said source to said cylinder, a trip device operable to release said latch to trip the breaker, means operable to simultaneously cause opening of the dump valve, and a manually operable closing lever having a mechanically-trip-free connection to the breaker, said latch when released tripping said breaker free of said closing lever.

18. Operating mechanism for a circuit breaker comprising a manually operable closing lever for closing the breaker, said lever being pivoted to a fixed support, a manually operable latch for holding the lever in closed position, a fluid motor for closing the breaker, a breaker lever pivotally connected to the closing lever and having a non-trip-free connection to the breaker, means operatively relating the breaker lever to the fluid motor in a non-mechanically trip free manner, a latching means engageable with said breaker lever for releasably holding the breaker closed, means for supplying fluid pressure to said fluid motor for closing the breaker, a dump valve for exhausting fluid from said motor to permit high speed opening of the breaker notwithstanding the supply of fluid pressure to said motor, means operable to release said latching means to thereby trip the breaker, and for simultaneously causing opening of said dump valve.

JAMES M. CUMMING.
